COMBINED CIGARETTE HOLDER AND EXTINGUISHER ATTACHMENT FOR AN ASH TRAY OR SIMILAR ARTICLE

Donald J. O'Connor, East Hartford, Conn.

Application March 11, 1957, Serial No. 45,197

Term of patent 14 years

(Cl. D85—2)

FIG. 1

FIG. 3

Fig. 1 is a perspective view of a combined cigarette holder and extinguisher attachment for an ash tray or similar article, showing my new design;

Fig. 2 is an enlarged side elevation thereof; and

Fig. 3 is an enlarged top plan view thereof.

The broken line showing of certain portions of an ash tray in Fig. 1 is for illustrative purposes only.

I claim:

The ornamental design for a combined cigarette holder and extinguisher attachment for an ash tray or similar article, as shown and described.
